[57] **CLAIM**

The ornamental design for a drinking glass stem, as shown and described.

DESCRIPTION

FIG. 1 is a front elevational view of a drinking glass stem showing one embodiment of my new design;

FIG. 2 is a top plan view thereof taken along line 2—2 of FIG. 1;

FIG. 3 is a sectional view thereof taken along line 3—3 of FIG. 1;

FIG. 4 is a sectional view thereof taken along line 4—4 of FIG. 1;

FIG. 5 is a sectional view thereof taken along line 5—5 of FIG. 1;

FIG. 6 is a bottom plan view thereof, and,

FIG. 7 is a front elevational view of a drinking glass stem showing another embodiment of my new design.

FIGS. 2, 3, 4, and 6 are also representative of the second embodiment except that the second embodiment has a wider diameter base and shorter, thicker stem.

The broken line showing of an upper portion of a drinking glass in FIGS. 1 and 7 is for illustrative purposes only and forms no part of the claimed design.
